Inventor

THEODORE WENK,
By his Attorney

S. S. Edwin.

UNITED STATES PATENT OFFICE.

THEODORE WENK, OF BROOKLYN, ASSIGNOR TO E. J. BROOKS & COMPANY,
OF NEW YORK, N. Y.

SHACKLE-WIRE FOR SEALS.

SPECIFICATION forming part of Letters Patent No. 434,219, dated August 12, 1890.

Application filed January 26, 1886. Serial No. 189,827. (No model.)

To all whom it may concern:

Be it known that I, THEODORE WENK, a citizen of the United States, residing at Brooklyn, in the State of New York, have invented 5 a new and useful Improvement in Shackle-Wires for Seals, of which the following is a specification.

This invention relates to shackles for that class of seals which have seal-disks of soft 10 metal within which one or both ends of the shackle are secured by compressing the disk in a seal-press. It relates to that class of shackles which are made of single wire, and it is more particularly an improvement on the 15 invention of Edward J. Brooks, set forth and claimed in Patent No. 192,735, dated July 3, 1877.

The present invention consists in shackles of round wire provided with certain pecu- 20 liarily-formed "bent-up" anchoring projections or "stops" adapted to resist with superior efficiency the withdrawal of the anchored shackle ends after the seal is pressed, and in a novel and simple method of forming the 25 preferred type of said stops and other bent-up anchoring projections, as hereinafter set forth.

A sheet of drawings bearing eighteen figures accompanies this specification as a part 30 thereof.

Figure 1 of the drawings is an elevation of a partly-formed shackle. Fig. 2 is an elevation of the same finished and looped, and Figs. 3 and 4 are magnified detail views of 35 one end thereof, illustrating this invention. Figs. 5 to 8, inclusive, and Figs. 9 to 12, inclusive, are like series of views representing two modifications. Figs. 13 and 14 are elevations of another shackle end, on the same scale as 40 Figs. 3 and 4, showing its anchoring enlargements, respectively, partly formed and finished. Figs. 15 and 16 are a similar pair of views of another shackle end, and Figs. 17 and 18 are respectively large and small scale 45 views of another shackle end representing a last modification.

Like letters of reference indicate corresponding parts of the respective shackles in the several figures.

50 In carrying out this invention I produce a

shackle A or A² or A³ or A⁴ or A⁵ or A⁶, of single round wire, which may be of a small gage, provided at one or both ends with bent-up anchoring projections or stops s or s² or s³ or s⁴ or s⁵ or s⁶. These are preferably formed 55 on both ends of each shackle, as shown in Figs. 2, 6, and 10, and a short distance from each extremity of the wire, as represented. After passing the shackles through a pair of car-door staples C, Fig. 2, or otherwise applying the seals, the free ends are threaded through or introduced into soft-metal seal-disks D, Figs. 2 and 14, which are then solidified around such ends in the seal-press in customary manner, whereupon their said 60 anchoring-stops operate to preclude the withdrawal of the wire without breaking it. One end of each shackle may preferably be made fast in the seal-disk preliminarily, as by casting the disk thereon. 70

The typical species of my shackle is A⁴, Figs. 13 and 14. Its anchoring-stops s⁴ project at right angles to the length of the wire to any required extent, so as to secure absolutely safe anchorages—that is to say, to insure a resistance to withdrawal exceeding the 75 tensile strength of the wire.

The shackle A⁶, Figs. 17 and 18, has stops s⁶, which are substantially similar to said stops s⁴ in construction and mode of operation. They are not, however, produced in the same manner apart from being bent up, and the method of producing said stops s⁶ forms no part of my present invention. 80

The method of forming said stops s⁴ is common to all except said stops s⁶, and is as follows: The annealed wire is bent back and forth around staggered pins in open jakes, varying in number and arrangement according to the form of stop that is to be produced, and assumes at the end of this operation the appearance represented by Figs. 1, 5, 9, 13, or 15, as the case may be. Its bends are now simply compressed by pressure substantially at right angles or perpendicular to 90 the sides of the bends, as illustrated by arrows in Figs. 1, 5, 9, 13, and 15, so as to close them and properly distribute them, when the shackle assumes the finished form represented by Figs. 3, 7, 11, 14, or 16. This method may be carried 95 100

out by means of hand-tools or automatic machinery, and the number and proportions of the bends may vary without departing from this invention.

- 5 An important advantage of the method is its adaptation to produce stops of any desired number of added thicknesses from two up, or of any required length of bend where length is effective, as illustrated by the drawings.
- 10 I am aware of the flat wire shackles with bent-up stops shown in Patent No. 298,665, dated May 13, 1884, and hereby disclaim the same as forming no part of my invention. Their only stops are adjusting-stops, which 15 coat with the upper edge of the seal-disk. My stops are anchoring-stops inclosed within the seal-disk, as illustrated in Figs. 2 and 14. Moreover, my invention is confined to round wire, the bends of which close up differently 20 from like bends in flat wire, as illustrated by Figs. 4, 8, and 12.
- I am also aware of the bent-up anchoring-enlargements set forth in Patent No. 278,866, dated June 5, 1883, and disclaim them as forming no part of my invention. Such enlargements are readily formed and are in practice 25 produced by coiling the wire to form a single

circular loop and then compressing such loop, as set forth at lines 4 to 7, page 2, of the specification of said patent. By my different process other and different and particularly larger and more prominent anchoring-enlargements are produced, as shown by my drawings.

Having thus described my said improvement in shackle-wires for seals, I claim as my 35 invention and desire to patent under this specification—

1. A shackle-wire for seals, composed of single round wire having bent-up anchoring-stops with their sides at or substantially at 40 right angles to the length of the wire, substantially as herein specified.
2. The within-described method of making shackle-wires of single round wire with bent-up anchoring-stops—namely, first bending the 45 annealed wire in open fakes, and, secondly, closing and properly disposing its bends by compressing them by pressure substantially perpendicular to their sides, for the purposes set forth.

50 THEODORE WENK.
